UNITED STATES PATENT OFFICE.

WILLIAM MOODIE YEOMANS, OF HANCOCK, NEW YORK.

HAIR-RIBBON PIN.

No. 926,450.

Specification of Letters Patent.

Patented June 29, 1909.

Application filed June 4, 1908. Serial No. 436,614.

To all whom it may concern:

Be it known that I, WILLIAM MOODIE YEOMANS, a citizen of the United States, and a resident of Hancock, in the county of Delaware and State of New York, have invented a new and Improved Hair-Ribbon Pin, of which the following is a full, clear, and exact description.

The object of the invention is to provide a new and improved hair ribbon pin, more especially designed for use on women's hair, to securely hold a hair ribbon, to display the bow thereof to the greatest advantage and to give the pin a buckle appearance.

15 The invention consists of novel features and parts and combinations of the same, which will be more fully described herein-after and then pointed out in the claims.

A practical embodiment of the invention 20 is represented in the accompanying drawings forming a part of this specification, in which similar characters of reference indicate corresponding parts in both views.

Figure 1 is a perspective view of the improvement; Fig. 2 is an edge view of the same; Fig. 3 is a reduced rear face view of the improvement and showing a bow in position thereon; and Fig. 4 is a perspective view of the improvement as applied.

30 The hair ribbon pin is preferably made from a single piece of sheet material, such as tortoise shell, celluloid, rubber, metal or the like, and the material is cut to form a plate A, curved transversely, as plainly shown in Fig. 2, to receive in its hollow portion a ribbon to be displayed. From the lower edge of the plate A extends integrally in a downward direction, the double hair pin B, adapted to engage a woman's hair, to hold the device in position on the head of the wearer.

From the lower edge of the plate A extend integrally and upwardly clamping arms C, curved outward or in a reverse direction to the curvature given to the plate A, the arms 45 C being located on opposite sides of an aperture D formed in the plate A, to give the latter a buckle appearance. Now by the arrangement described, the hair ribbon can be readily passed between the plate A and the

50 clamping arms C, to securely clamp the hair ribbon in place, with a view to properly display the bow of ribbon, the middle portion of which projects in the aperture D, the ends of

the bow projecting beyond the sides of the plate A as plainly shown in Figs. 3 and 4.

Although I have shown the plate A of rectangular form and the double hair pin B extending in a downward direction, it is evident that the form of the plate A or the direction of the double hair pin B may be varied, without deviating from my invention.

Having thus described my invention, I claim as new and desire to secure by Letters Patent:

1. A hair ribbon pin, comprising an elongated plate having a longitudinally extending opening, a retaining means depending from the plate for engagement with the hair of the wearer, and a clamping device on one face of the plate and operating in conjunction with the said plate for holding the ribbon in place with a portion projecting into the aperture of the plate.

2. A hair ribbon pin, comprising a curved apertured plate, pins extending integrally from the lower edge of the said plate in a downward direction for engagement with the hair of the wearer, and clamping arms extending integrally from the one edge of the plate and projecting in direction of the opposite edge of the plate, said arms operating in conjunction with the plate for holding the ribbon in place.

3. A hair ribbon pin, comprising a longitudinally curved and apertured plate, pins extending integrally from the lower edge of the said plate in a downward direction for engagement with the hair of the wearer, and clamping arms extending integrally from the lower edge of the plate in an upward direction on opposite sides of the aperture in the said plate, the said arms being curved in an opposite direction to the plate.

4. A hair ribbon pin having a concavo-convex head apertured and provided with means on the concave side of said head for clamping a ribbon thereto with a portion thereof projecting into the said aperture.

In testimony whereof I have signed my name to this specification in the presence of two subscribing witnesses.

WILLIAM MOODIE YEOMANS.
